UNITED STATES PATENT OFFICE.

CHARLES FOURNIER, OF GENEVA, SWITZERLAND.

APPARATUS FOR THE ELECTROLYTIC DECOMPOSITION OF ALKALI CHLORIDS.

SPECIFICATION forming part of Letters Patent No. 734,812, dated July 21, 1903.

Application filed June 25, 1902. Serial No. 113,169. (No model.)

To all whom it may concern:

Be it known that I, CHARLES FOURNIER, chemist, a citizen of the Republic of France, residing at Geneva, in the Republic of Switzerland, have invented certain new and useful Improvements in Apparatus for the Electrolytic Decomposition of Alkaline Chlorids, of which the following is a specification.

The electrolytic production of chlorin and caustic soda from common salt takes place almost universally by the use of suitable porous partitions which divide the electrolytes into chambers—that is to say, the cathode-chamber, in which the caustic soda accumulates, and the anode-chamber, in which the chlorin accumulates. No matter what form is given to the diaphragm and of what material it is made it has, however, hitherto been impossible to obtain a quantity of chlorin and caustic soda equivalent to the electrical energy consumed; but in the best arrangements a yield not exceeding eighty per cent. is attained. The loss of energy thus resulting is to be ascribed to the mutual action of chlorin and soda solution; and the present invention has for its object to avoid this action. For a better explanation the following theoretical considerations must necessarily be considered. Let us assume two fluids (which to facilitate description will be referred to as A and B) separated by a porous partition and that fluid A contains a substance which will be referred to as *a*, which is soluble in fluid B. According to the law of diffusion-pressure a portion of the substance *a* must travel from A to B and there be dissolved, and the amount thus traveling is the more considerable the greater the solubility of *a* in B. By exerting a pressure on B which is greater than that bearing on A the transmission of *a* to B may indeed be considerably diminished; but by the use of this means, again, a larger portion of B is forced through the pores of the diaphragm—that is to say, mingles with A. If in addition the liquid B is in a position to chemically combine with *a*, forming a soluble compound *b*, the hereinbefore-mentioned action of the diffusion-pressure is still further increased. This is the case to a still greater extent if B in turn can act chemically on *b*, forming a soluble compound *b'*, which in turn may further react, if desired, with *a*. The appear-

ances arising in the electrolysis of chlorid-of-sodium solutions by the use of diaphragms correspond exactly to the circumstances hereinbefore depicted and cause a defective yield. The cathode fluid A contains caustic soda *a* in solution. The anode fluid B is charged with chlorin, which reacts with soda solution, forming soluble hypochlorite *b*, according to the equation:

The sodium hypochlorite in solution in B is converted into the following in consequence of the continued formation of chlorin:

In the present case *b* and *b'* may even act one on another, forming hydrochloric acid as a by-product,

so that finally the anode fluid B always contains an excess of free hypochlorous acid, which according to the foregoing is a great drawback in the carrying out of the process. With the reactions shown, which may take place in the diffusion of the caustic soda to the anode-chamber, the series of possible transformations is not at all exhausted; but it is evident without further explanation that where simple porous diaphragms are unconditionally used a considerable quantity of caustic soda must pass over to the anode-chamber and that it is also impossible to prevent chlorin and chlorin compounds from passing over to the cathode-chamber. It was evidently considerations of this kind which led to the use of two porous partitions arranged parallel with a small space filled with salt solution between them instead of a single partition. On this salt solution pressure is exerted, and thus the passing over of the caustic soda and chlorin into the other compartment is prevented. This process, however, is unable to be carried out technically, as so strong a pressure must be applied in order to obtain a practical result that it is difficult, if not impossible, to make suitable diaphragms of a suitable material. Their

to be considered, however, and that is that the more caustic soda is contained in the cathode liquid in the cathode-cell k the greater will be the tendency it has to pass over into 5 the middle cell m , and therefore the greater must be the counter-pressure in this cell. This may, for instance, be obtained by arranging several cathode-cells k in such a way that the cathode liquid (the caustic-soda contents 10 of which constantly increases) flows through all the cells in succession and imparting to each of these cathode-cells in any suitable manner a higher difference of pressure than the preceding one as compared with that of the 15 middle cell m . The following means (shown in Fig. 2) may also be employed: Here the cathode-cell k is divided into several superimposed compartments, the uppermost of which receives the fresh chlorid-of-sodium solution, 20 while by a suitable means of circulation, which will be hereinafter explained, care is taken that the lower compartments are supplied with liquid already containing a higher quantity of caustic soda in such a way that the 25 lowermost compartment shows the highest caustic-soda contents. In this manner there is obtained a suitable grading down of the counter-pressure exercised by the middle cell, corresponding to the varying caustic-soda contents. 30 The action of this division into compartments is also supported by a variation in the thickness of the porous wall p of the separate superimposed compartments of the cell, as shown in Fig. 2, which wall separates the 35 cathode-chamber from the middle cell. A very important result is also obtained by this arrangement—namely, that less liquid from the middle cell m penetrates into the cathode-cell k according to the increasing thickness 40 of the wall. In the middle cell m a metallic superoxid—for instance, cobalt superoxid, as already explained in the preliminary theoretical argument—is introduced, and this takes place, preferably, by saturating pieces 45 of pumice with nitrate of cobalt, then rendering same incandescent, and then packing them loosely in the middle cell m . The further necessary heating of the liquid in this cell m takes place, preferably, outside the apparatus, as shown in Fig. 3. In this arrangement the salt water, which has become cool, leaves the middle cell m through a pipe b , which communicates with a vessel c , into which fresh solution runs from a tap d . From 55 the vessel c the solution flows to a heating apparatus e of any suitable kind, from whence it is lifted to a feed-tank f , which is arranged at a height determined according to the degree of hydraulic pressure, as the solution 60 turns again to the cell m from this tank through a pipe g . Such a quantity of salt solution is also withdrawn from the pipe b of the middle cell m as is necessary for completing the contents of the cathode-cells k , a 65 valved or other regulated passage or pipe h being provided to allow liquid to flow into the

lower part of the uppermost cell and from the upper part of each cell to the lower part of the one below, and so on through the superimposed series. A similar circulation takes 70 place for the anode-cell a as that described for the middle cell m . A pipe i , having an upwardly-directed bend in which any escape of chlorin, owing to variations of the level of the liquid in the anode-cell a , is prevented, 75 leads to a device l , which automatically replaces the salt contents of the solution, and thence to a lifting device n , which feeds a tank o , from whence a pipe q conveys the return flow of the liquid to the cell a . To complete 80 the explanation of the arrangement shown in Fig. 3, it must also be mentioned that hydrogen formed in the cathode-cells k escapes through a small pipe r and that there is also a pipe s for drawing off the chlorin escaping from the anode-cell a . The anode t itself may, for instance, be a carbon anode. A large number of these arrangements, which are operated simultaneously, may be fed from the same tanks by means of pipes common to 90 all, and also the heating and salt-replenishing devices (e and l) may simultaneously serve for a similar series of decomposing apparatuses.

In order to complete the explanation, a 95 complete form of construction of the apparatus is shown in vertical section in Fig. 4 and horizontal section in Fig. 5. It must first be pointed out that the middle cell m instead of being bordered by two porous walls p and p' may also be formed by a channel-like 100 cell or a group of such channels being arranged in one wall formed of the porous material. Further, the whole apparatus instead of being based on a rectangular ground plan 105 may also be cylindrically arranged. Such an arrangement is shown in Figs. 4 and 5. In this case the porous wall is formed of separate superimposed annular disks strongly 110 pressed one upon another and of a suitable material—such, for instance, as asbestos. Each of these disks has a circular central opening, all of similar diameters. The combined central opening traverses the whole apparatus vertically, thus forming an anode-cell a . At the uniform distance from the center point each disk also has a number of circular openings, which after the disks have 115 been superimposed traverse also the entire height of the apparatus and as a whole form 120 passages which act as the middle cell m . By the choice of various sizes of rings the differences in the thickness of the walls between the middle cells m and the various compartments of the cathode-cell a is obtained. Between the separate sections of the whole porous cell thus formed slate disks u are 125 placed. These have similar perforations and are of a similar diameter to the asbestos disks, thus allowing the anode-cell a and the 130 passages m of the middle cell to pass through the entire apparatus. The porous cell rests

below also on a slate disk *v*, forming the bottom of the anode-chamber *a*. As it is also perforated in the manner shown, all the passages *m* may connect with an annular collecting-passage situated in a cast-metal piece forming a socket or foot and on which the whole apparatus is built. A pipe *g* leads from the annular passage to the feed apparatus, which corresponds to the tank *f* of Fig. 3. The cell is closed at the top by a piece of slate, which also is perforated to correspond to the asbestos disks. The central perforation corresponding to the anode-chamber *a* traverses the disk completely. The continuations of the passages *m* extend, however, only up to half the height and communicate laterally with an annular space, which is formed partly by the piece of slate and partly by an outer casting. A pipe *b* conveys the chlorid-of-sodium solution flowing out from the passages *m* to the heating apparatus *e*, Fig. 3. In Figs. 4 and 5 the connections of the electric current are designated by the letters *y* and *z*. The cathode-cell *k* is formed of three superimposed cast-iron hollow cylinders, which correspond to the three sections of the porous partition, which vary in their outer diameter. They rest on slate pieces *u* and are so formed that they may be socketed one in the other like pipes. Perforated flanges cast on them allow of a firm connection by means of bolts adapted to be tightened up. By this means the necessary coherence is imparted to the porous cells, and the whole apparatus receives the necessary stability. The cylinder-walls form also the cathodes. In order to form a water-tight joint for the whole apparatus, the joints *w* are filled with a suitable material—such, for instance, as a molten mixture of tar and Portland cement—after the parts of the apparatus have been put together. The anode *t* is in this case a hollow cylinder of carbon which carries at its upper end a lead cover closing the cell. All the rest will be readily understood by reference to Fig. 3.

The apparatus hereinbefore described may also be employed for the electrolysis of other alkaline chlorids.

50 I declare that what I claim is—

1. In an apparatus for the electrolysis of alkaline chlorids, an anode-compartment, a cathode-compartment, comprising a plurality of separate cells superimposed upon and in communication with each other, and an intermediate compartment, said anode and cath-

ode compartments being separated from said intermediate compartment by porous walls.

2. In an apparatus for the electrolysis of alkaline chlorids, an anode-compartment, a 60 cathode-compartment comprising a plurality of separate cells superimposed one above another, and the upper portion of each cell being connected with the lower portion of the next lower cell by a pipe, and an intermediate 65 compartment, said anode and cathode compartments being separated from said intermediate compartment by porous walls.

3. In an apparatus for the electrolysis of alkaline chlorids, an anode-compartment having a porous wall, a cathode-compartment comprising a plurality of separate cells, superimposed one upon another and each having a porous wall of greater density than the wall of the next cell thereabove, and an intermediate compartment. 70

4. In an apparatus for the electrolysis of alkaline chlorids, an anode-compartment, a cathode-compartment comprising a plurality of separate cells superimposed one above another, and the upper portion of each cell being connected with the lower portion of the next lower cell by a pipe, and an intermediate compartment, the said anode and cathode compartments being separated from said intermediate compartment by porous walls, and the wall of each separate cell comprising said cathode-compartment being thicker than the wall of the next compartment above it. 80

5. In an apparatus for the electrolysis of alkaline chlorids, an anode-compartment, a cathode-compartment, and an intermediate compartment, said compartments being formed by asbestos disks superimposed upon each other each disk having a central perforation, a plurality of perforations between said central perforation and its periphery, and a plurality of perforations adjacent to its periphery, so that when said disks are assembled, the central perforations register together 95 to form the anode-compartment, the intermediate perforations register together to form intermediate compartments, and the outer perforations register together to form cathode-compartments. 100

In testimony whereof I have hereunto set my hand in presence of two subscribing witnesses.
